UNITED STATES PATENT OFFICE.

ONESIME PAULHUS, OF QUIDNICK, RHODE ISLAND.

GUARD-RAIL SUPPORT FOR RAILROADS.

SPECIFICATION forming part of Letters Patent No. 727,999, dated May 12, 1903.

Application filed October 9, 1902. Serial No. 126,394. (No model.)

To all whom it may concern:

Be it known that I, ONESIME PAULHUS, a citizen of the United States, residing at Quidnick, in the county of Kent and State of Rhode Island, have invented a new and useful Improvement in Guard-Rail Supports for Railroads, of which the following is a specification.

This invention has reference to an improvement in the rail-supports used in connection with railroad-curves to guide the wheels in passing the curves or on bridges.

The invention consists in the peculiar and novel construction of the support and the means for securing the rails, as will be more fully set forth hereinafter.

When a curve is reached on a railroad-track, the wheels of the cars on the inner side will bear to the center. Without a guard-rail all the weight of the cars would be brought on the flanges of the inner wheels. By reason of the guard-rail both sets of the flanges of the wheels are brought into use, the inner set on the rail proper and the outer on the guard-rail.

Figure 1 is a plan view of my improved guard-rail support, showing the main rail and the guard-rail secured thereto. Fig. 2 is a side view of the guard-rail support, the main rail and guard-rail being shown in section. Fig. 3 is a longitudinal sectional view of my guard-rail support, showing the same as adapted to a modified form of guard-rail. Fig. 4 is a transverse sectional view of the support, showing the wedge-shaped locking-block secured to the supporting-base by means of screw-bolts.

In the drawings, *a* indicates a base or chair on which the through-rail *b* rests.

a' indicates a plane raised above the plane on which the through-rail *b* rests, on which plane *a'* the guard-rail *b'* is supported. The base is provided near one end with the abutment *a*², the inner face of which is preferably inclined inward and is provided near the opposite end with the abutment *a*³. The lugs *a*⁴, projecting from the ends of the base or chair, serve to secure the base to the tie and may be constructed in any usual manner to secure the base to the railroad-tie. The base *a* is provided with the transverse slot *a*⁵.

In the preferred form when a T-rail is used to form the guard-rail *b'*, as shown in Fig. 2,

the block *b*², preferably provided with the lugs *b*³ and formed to fit the shoulder and the foot of the T-rail and having the surface in contact with the surface of the abutment *a*² inclined, is placed between the abutment *a*² and one side of the through-rail *b*. Between the through-rail *b* and the guard-rail *b'* is placed the distance-block *b*⁴, the opposite ends of which are shaped to closely bear against the two adjacent sides of the through-rail *b* and guard-rail *b'*. The block *b*⁵, having a central raised surface *b*⁶ and closely fitting against the side of the T-rail, is placed against the other side of the T-rail. The wedge-block *b*⁷ bears against the abutment *a*³ and the beveled surface of the block *b*⁵ and engages, by means of the groove *b*⁸, with the inclined and raised surface *b*⁶ of the block *b*⁵. The wedge-block *b*⁷ preferably extends beyond the width of the base *a* and is perforated near the ends to receive the bolts *b*⁹ and *b*¹⁰. The bolt *b*⁹ is preferably screw-threaded on both ends, is bent at right angles, and inserted through the elongated slot *a*⁵. The bolt *b*¹⁰ is provided at its lower end with an eye through which the screw-threaded end of the bolt *b*⁹ extends and to which it is secured by the nut *b*¹¹. The wedge-block *b*⁷ is forced down between the block *b*⁵ and the abutment *a*³ by means of the screw-nuts *b*¹² *b*¹², on which, if desired, lock-nuts may be used. When the base is firmly secured to the tie, the strain on the guard-rail is firmly resisted by the abutment *a*³, the wedge-block *b*⁷, and the block *b*⁵, and any looseness or wear may be readily taken up by turning the screw-nuts *b*¹² *b*¹² and forcing the wedge-block down on the block *b*⁵.

In the modified form (shown in Fig. 3) the guard-rail is in the form of a flat plate set between the blocks *b*⁴ and *b*⁵. In this form the face of the block *b*⁵ is made to conform to the flat side of the guard-rail, and the face of the block *b*⁴ is also made to conform to the flat side of the guard-rail against which it bears.

In the modified form of construction I prefer to secure the block *b*⁴ and the block *b*⁵ to the flat guard-rail by means of the bolt *b*¹³.

Having thus described my invention, I claim as new and desire to secure by Letters Patent—

1. In a guard-rail support, the combination with the through-rail and the guard-rail, of

blocks comprising a distance - block held between vertically-inclined surfaces, as described.

2. In a guard-rail support, the combination 5 of a base or chair, abutments on the chair, blocks bearing against the opposite surfaces of the rails, a wedge-block, and bolts connected with the base and with the wedge-block, as described.

10 3. In a guard-rail support, the combination with the base or chair a , the abutments a^2 and a^3 , the through-rail b and the guard-rail b' , of the block b^2 , the distance-block b^4 , the block b^5 , the wedge-block b^7 and means for securing 15 the wedge-block in the adjusted position, as described.

4. In a guard-rail support, the combination with the base a , the oblique abutment a^2 , the abutment a^3 and the slot a^5 in the base, of the through-rail b the guard-rail b' , the block b^2 , 20 the blocks b^4 and b^5 secured to the guard-rail by the bolt b^{13} , the wedge-block b^7 and the bolts b^9 and b^{10} secured in the slot a^5 and provided with the nuts b^{12} b^{12} , as described.

In testimony whereof I have signed my 25 name to this specification in the presence of two subscribing witnesses.

ONESIME PAULHUS.
